UNITED STATES PATENT OFFICE.

THOMAS W. GODWIN, OF PORTSMOUTH, VIRGINIA.

IMPROVEMENT IN OIL-CUPS FOR MACHINERY.

Specification forming part of Letters Patent No. 40,032, dated September 22, 1863.

To all whom it may concern:

Be it known that I, THOMAS W. GODWIN, of Portsmouth, in the county of Norfolk, in the State of Virginia, have invented a new and useful Improvement in Machinery Oil-Cups; and I do hereby declare that the following is a full and exact description thereof, reference being had to the accompanying drawing, which represents a sectional elevation of my improved oil-cup, with the letters of reference marked thereon.

In this drawing, A represents the upper reservoir, into which the oil is poured from the can, and whence it passes into the lower reservoir, B. From B it flows through the apertures I into the box K, from which it continues its course around and past the valve L into the box S. If the valve L is in the position shown in the drawing, the oil passes directly from the box S into the tube C, and through that to its destination; but if the valve L is depressed to the bottom of the box S the oil moves from the space around the valve, through the passages m m m to the center of the valve, where it meets and enters the tube C. It is to control the passage of the oil, as above described, under pressure, from the reservoir A to the tube C, that the machinery shown in the interior of the oil-cup is invented. That machinery consists of two valve stems, D and G, the upper end of the latter screwing into the lower end of the former, as shown at H in the drawing.

E represents a valve, firmly attached to and moving with the stem D, and setting or closing upward, so that when closed it effectually prevents the escape of any fluid from one reservoir to the other.

L represents another valve, firmly attached to and moving with the lower stem, G. The stem G is square below the threads of the screw, and is accurately fitted to a square aperture in the plate n n, which covers the box K, and which is held firmly in a fixed position by teeth and sockets, or their equivalents, at n n, that are not shown distinctly in the drawing. This cover being thus fixed, the stem G, itself square, and moving in a square aperture in the cover, is equally fixed and held in one position, while the upper stem, D, being round and moving in a circular aperture, can be turned at pleasure—an arrangement which enables us, by turning the upper

stem in one direction or the other, to increase or diminish at will the distance between the two valves E and L. The valve L sets or closes upward against the under side of the box K, forming, when closed, a part of the bottom of that box, so that when the valve is set or closed no fluid can pass between the boxes K and S. The valve itself is of a cylindrical form, and fits into the cylindrical box S so loosely as to permit the easy passage of any fluid between it and the walls of the box. The under side of the valve is cut with deep grooves or channels, the ends of which are represented at m m m, and which pass diametrically across it, intersecting each other in the center of the valve, at the upper end of the tube C. By means of these channels, when the valve is depressed to the bottom of the box S, the communication is still kept open from the tube C to the space between the valve and the walls of the box S, and thence through the upper box, K, and the apertures I I into the globular reservoir B.

F is a spiral spring attached to the under side of the upper valve, E, and surrounding the contiguous portions of both valve-stems D and G, when they are in position as shown in the drawing, in which position it presses firmly upon the cover n n of the box K. The object of this spring is to force the valves E and L upward and keep them closed. If the tube C is connected with apparatus which allows it to be filled with the steam from the engine, the steam also presses the valve L upward and helps to keep it firmly set and closed. In this case, when the lower valve is open, the reservoir B becomes filled with steam, which may afterward be let off by the cock P, provided for the purpose. The whole lower portion of the apparatus, comprising the stem G, the box K and its cover n, the box S, and the metallic walls of the tube C, it will be observed, are connected together and can be together detached from the globular reservoir by unscrewing them, the thread of the screw by which they are attached to the reservoir at a a a a and the thread of the screw at the upper extremity of the stem G being of the same size, and screwing or unscrewing simultaneously and by the same movement. At b b b are threads cut around the walls of the tube C, by which the whole apparatus can be screwed to the machinery upon which it is to

work. This drawing represents the different parts of my improved oil cup, as thus described, screwed together and ready for use.

To enable those unacquainted with my invention to better understand its practical working, I will endeavor to briefly describe its operation.

Suppose that the different parts of the apparatus are in the position represented in the drawing, both valves being firmly closed and held closed by the spiral springs F. Now, if we move the handle R toward us and to the left, it screws the lower part of the stem D down farther upon the upper part of the stem G, and causes the upper valve, E, to descend and open the passage between the two reservoirs. Meanwhile the spiral spring F, assisted by the steam below, keeps the lower valve closed. If, then, the upper reservoir, A, had been filled with oil or other fluid, it would, upon thus moving the handle R, flow at once into the lower reservoir and into the box K K, where it would be held. If, now, the motion of the handle R is reversed, the stem D unscrews and rises, again closing the valve E, and cutting off the communication between the reservoirs; but if the handle be still further turned in the same direction, it is evident that the process of unscrewing the two valve-stems from each other still continues, and that since the valve E, now firmly set against the upper surface of the reservoir B, prevents the upper stem from rising any farther, the lower stem must begin to move in the opposite direction, or downward. This at once opens the passage below. The oil flows downward from the box K K upon the upper surface of valve L, thence passes around the loosely-fitting sides of the valve into the lower part of the box S, thence under the valve, or, if it is depressed to the bottom of the box, through the channels m m to the tube C, thence to the machinery, thus admitting the oil to the cylinder or machinery under any pressure of steam, without permitting the escape of the steam during the process.

I am aware that an oil-cup in many respects similar to mine, containing the two reservoirs

A and B and two valves with an upright shaft occupying nearly the position which mine does, was patented June 22, 1858, by Messrs. Ross and Holland, of Philadelphia, Pennsylvania; but without infringing upon that patent my invention accomplishes everything claimed for theirs, and has obvious advantages over it; and, first, it is less liable to get out of order. In mine the unscrewing of the stems D and G can only be continued till the valve E is closed and the valve L is at the bottom of the box S. In that of Messrs. Ross and Holland, however, the screw-plug which takes the place of the stem G and the valve L in my invention may be unscrewed so far as to fall out of its place and derange the working of the whole machinery. In the invention of Messrs. Ross and Holland the upper valve, which separates the reservoirs A and B, is actuated and held in position by a spring only. In mine, on the contrary, it is held in position by both a spring and a screw. In the former patent the spring is outside of the cup and exposed to the weather, and is liable to corrode and get out of repair. In the invention for which I claim a patent, the spring is secured from the action of the weather, and is constantly lubricated by the oil of the machinery. In the patent of Messrs. Ross and Holland the upright shaft corresponding to the stem D of my invention incloses or "keys" upon the square screw-plug, and is not otherwise connected with it. In my invention it screws firmly to the lower stem, G, forming with it a durable and permanent connection, and strengthening the whole apparatus.

What I claim as my invention, and desire to secure by Letters Patent, is—

1. The arrangement, within an oil-cup, of the valve L, or its equivalent, the valve stem G, and the cap N, as shown and described.
2. The arrangement, within an oil-cup, of the stems G and D and their valves, when constructed and operated substantially as shown and described.

THOS. W. GODWIN.
